DOOR LOCK

Walter R. Schlage, Burlingame, and Ward H. Hahir, San Mateo, Calif., assignors to Schlage Lock Company, San Francisco, Calif.

Application July 12, 1943, Serial No. 494,296

1 Claim. (Cl. 292—140)

This invention relates to a door lock, and especially that type known as a rim lock latch in which a sliding latch or bolt is operated from the inside by a knob or handle, and from the outside by means of a key.

The object of the invention is to generally improve and simplify the construction and operation of locks of the character described; to provide a lock in which comparatively few parts are required, and which combine to produce a durable longlived structure; to provide a lock in which practically all parts including the housing may be made from sheet steel or other sheet metal by punch press operation, and in which the latch or bolt together with the retractor plate is made as a single unit assembled from laminated parts; to provide a combined latch bolt and a retractor plate which is recessed on opposite sides to receive the actuating mechanism, thereby permitting a compact space saving assembly of parts; and, further, to provide means for dead locking the latch bolt in projected and retracted position.

The lock is shown by way of illustration in the accompanying drawings, in which:

Fig. 1 is a side elevation of the door lock looking from the inner face thereof and showing the base plate removed, said view also showing the latch bolt in retracted position;

Fig. 2 is a view similar to Fig. 1 but it is partially broken away, and different from Fig. 1 in showing the rollback member 17 in a position where it has raised the deadlocking member out of engagement with the deadlocking lug;

Fig. 3 is a view similar to Fig. 1 showing the latch bolt in projected position;

Fig. 4 is a cross section of a complete door lock taken on line IV—IV of Fig. 1;

Fig. 5 is a horizontal section taken on line V—V of Fig. 4;

Fig. 6 is a perspective view of the arms 26 which carry the deadlocking member;

Fig. 7 is a perspective view of the inner handle and spindle;

Fig. 8 is a perspective view of the rollback member 18 which cooperates with the inner spindle and handle;

Fig. 9 is a perspective view of the rollback member 17;

Figs. 10 and 11 are perspective views of the latch bolt and connected retractor plate looking from opposite sides thereof;

Fig. 12 is a perspective view of the lock as a whole applied to a door; and

Fig. 13 is a perspective view of the lock as a whole before being applied to a door.

Referring to the drawings in detail, and particularly Fig. 12, A indicates the housing of a rim lock which is provided with a face plate B, said plate and housing being secured to the face and edge of a door by screws such as indicated at 2 and 3. Formed in the face plate is an opening 4 which serves as a guide and support for a latch bolt C, and formed integral with said bolt is a retractor plate D in which is formed a longitudinally extending slot 1.

The retractor plate and bolt is in this instance laminated in structure as it is formed of four plates indicated at 8, 9, 10 and 11, which may be riveted, spot welded or otherwise secured together. The plates 9 and 10 are extended to form the retractor plate D and the inner end of plate 10 is bent at right angles to form a shoulder 12. A similar shoulder 12a is formed on plate 8, and a dogging lug 14 is formed on the upper edge of plates 9 and 10. The bolt C as shown is formed of four plates which represents a thickness substantially equal to the space formed between the inner face of the cover plate 16 of the lock housing and an inner base plate 15. A recess or space is formed between the shoulders 12 and 12a on the retractor plate to receive a rollback member 17, and as plate 11 terminates at a point just behind the inner end of the bolt C, space is also formed in the opposite side of the retractor plate for the reception of a rollback member 18. This latter rollback member is secured as at 19 (see Figs. 4, 5, 7 and 8) to a spindle 20 which is journaled as at 21 in the cover 16 of the lock housing. A knob or handle 22 is secured on the outer end of the spindle and by rotating the knob and spindle, the rollback member may be swung back and forth. The rollback member carries a pin 23 which projects into a square shaped pocket 24 formed in the retractor plate (see Figs. 1, 2, 3 and 11); hence, when the rollback member 18 is swung either back or forth by means of the handle 22, pin 23 will engage one side wall or another of the pocket and thereby project or retract the latch bolt.

By referring to Figs. 1, 2 and 3, it will be noted that the pocket 24 has a width substantially twice the diameter of pin 23. This allows a certain amount of free movement of the rollback member 18 without imparting movement to the retractor plate and latch bolt. This free movement is important as the rollback member has two functions—first, that of releasing a dogging member 25 with relation to the dogging lug 14, and second, that of projecting or retracting the latch bolt. The dogging member 25 is secured between

a pair of spaced arms 26 which are pivoted in the lock housing at the point 27. A spring 28 is interposed between the lock housing and the dogging member 25, thereby normally holding it in engagement with the dogging lug 14. It is accordingly necessary to raise the dogging member 25 away from the lug 14 before the latch bolt can be either projected or retracted, and this is accomplished during the free movement of the rollback member 18 as the flattened upper end 18b will during this movement engage the lower edge of the outermost arm 26 and thereby raise the dogging member sufficiently to clear the lug 14. At the moment this has been accomplished, pin 23 on the rollback member will engage the opposite side wall of the pocket 24 and further movement of the rollback member will thus cause projection of the latch bolt and cause it to assume the position shown in Fig. 3.

Retraction of the latch bolt by handle 22 and the roll-back member 18 is accomplished in the same manner as pin 23 will have free movement from one side wall of the pocket 24 to the other before it begins to impart retracting movement to the latch bolt. During this movement, the upper end 18c of the rollback member again engages the outermost arm 26 and raises the dogging member and thereafter causes retraction of the latch bolt.

The description so far submitted describes operation of the lock from the inner side of a door only. To operate the lock from the outside or exterior surface, a standard form of key actuated pin tumbler lock 30 may be employed. The key actuated cylinder 31 of this lock is in the present instance provided with a spindle bar 32 square in cross section. This spindle bar projects through the hub 33 of a second rollback member 17 and into the hollow spindle 20 which carries the rollback member 18. The spindle bar 32 is freely rotatable in the spindle 20 thereby insuring independent operation of the key actuated rollback member 17. This member is best shown in Figs. 1, 2, 3 and 9. It is disposed in the space or recess formed between the shoulders 12 and 12a and assumes the position shown in Fig. 1 when the latch bolt is retracted. When a key is inserted in the pin tumbler lock and rotated in the direction of arrow a (see Fig. 1), the rollback member 17 will rotate in the same direction and will rotate free for a distance of substantially 180°, or until it assumes the position shown in Fig. 2 where it has engaged and lifted the dogging member 25 free of lug 14. The rollback member is then turned in the same direction another 180°, and during that movement engages shoulder 12a causing projection of the latch bolt, and finally swings away therefrom to assume the position shown in Fig. 3. To retract the latch bolt by means of the key, it is only necessary to turn it in the opposite direction. The rollback mem-

ber will then swing in the direction of arrow b (see Fig. 3) and will swing freely about 180° to first engage and lift the dogging member 25. During the next 180° of movement, it engages shoulder 12 and causes retraction of the latch bolt and finally assumes the position shown in Fig. 1. Thus the key actuated rollback member requires one complete rotation to retract or project the latch bolt while the rollback member 18 swings through an arc of 90° only from the position shown in Fig. 1 to that shown in Fig. 3 or vice versa to fully project or retract the latch bolt. Projecting and retracting movement of the latch bolt may be limited by the length of the slot 7 formed in the retractor plate or by engagement of the shoulders 12 and 12a with opposite sides of the rollback member 17. The latch bolt is dogged against movement both in its projected and retracted positions. The latch bolt is actuated either by manual or key operation, and each operates independently of the other. The lock as a whole is simple both in construction and operation. The individual parts required are few, and while this and other features of my invention have been more or less specifically described and illustrated, I nevertheless wish it understood that changes may be resorted to within the scope of the appended claim, and that the materials and finish of the various parts employed may be changed in accordance with the experience of the manufacturer, or as varying conditions may demand.

Having thus described our invention, what we claim and desire to secure by Letters Patent is:

In a lock of the character described, a housing, a latch bolt and a connected retractor plate slidably mounted in the housing, said latch bolt being laminated in construction and consisting of four united plates the two innermost of which are extended to form a retractor plate having a thickness about half that of the latch bolt so as to form a space between the lock housing and each side of the retractor plate, a pair of independently operated spindles journaled in opposite sides of the housing, a rollback member on each spindle and disposed on opposite sides of the retractor plate and in the spaces formed between the housing and opposite sides of the retractor plate, a dogging lug on the retractor plate, a spring actuated dogging arm normally engaging the dogging lug and deadlocking the latch bolt, and a pair of spaced shoulders formed on each side face of the retractor plate, said rollback members during rotation of either spindle first engaging the dogging arm and releasing it with relation to the dogging lug and then engaging one or another of the spaced shoulders on the side of the retractor plate adjacent thereto to either extend or retract the latch bolt.
